No. 719,644.

PATENTED FEB. 3, 1903.

A. CAREY.

DUMPING WAGON.

APPLICATION FILED JUNE 17, 1902.

NO MODEL.

UNITED STATES PATENT OFFICE.

ABNER CAREY, OF MILLS, PENNSYLVANIA.

DUMPING-WAGON.

SPECIFICATION forming part of Letters Patent No. 719,644, dated February 3, 1903.

Application filed June 17, 1902. Serial No. 112,071. (No model.)

To all whom it may concern:

Be it known that I, ABNER CAREY, residing at Mills, in the county of Potter and State of Pennsylvania, have invented certain new and 5 useful Improvements in Dumping-Wagons, of which the following is a specification.

My invention relates to dumping-wagons, and has for its object to provide a wagon that is simple in construction, easy to operate, 10 that consists of a very few parts, and is thus reasonable in cost of manufacture.

The advantages of my invention will more fully appear hereinafter and by reference to the accompanying drawings, in which—

15 Figure 1 is a top plan view of wagon-body showing my invention; Fig. 2, a plan view showing the position taken in dumping the load; Fig. 3, a cross-section on line 33 of Fig. 1; Figs. 4 and 5, detail views of the means 20 for pivoting the wagon-body to the frame, and Fig. 6 a detail view of one of the journaled beams.

In the drawings similar reference characters indicate corresponding parts throughout 25 the several views.

A designates the axle of a wagon; B, the bolster; C, cross-pieces resting on bolsters B; D, a beam secured to cross-pieces C, and E transverse bars secured to beam D at its 30 ends and in the center.

F represents beams journaled in metal loops G, secured on the ends of transverse bars E and in the ends of cross-pieces C, having transverse grooves near their ends, as shown 35 at H, and a strap I to pass over the beam F, said beam F being formed with circular journals K to fit said loops G and hollowed-out portions H and straps I.

L represents boards secured to beams F to 40 form the floor of the wagon-body, their abutting edges resting on the beam D when the wagon is not dumping, while M represents the side pieces, also secured to beams F.

N represents angular braces to secure the 45 beams F and floor L and side pieces M together.

O represents the end pieces secured to the floor and side pieces, and P a hasp and staple

or other suitable fastening means to hold the two halves of the body together when loaded. 50

Q represents sockets secured to each side piece M to receive a lever R to dump the load.

The operation of my invention will be readily apparent from an inspection of the drawings and the description above. 55

Having thus described my invention, what I claim is—

1. In a dumping-wagon, a beam secured to the axles, transverse bars secured to said beam, loops secured to each end of said transverse bars, beams having rounded portions journaled in said loops, and the wagon-body divided longitudinally into two sections, each of said sections being secured to one of said beams, substantially as shown and described. 65

2. In a dumping-wagon, cross-pieces secured to the bolsters having transverse grooves, beams having rounded portions resting in said grooves, straps passing over said 70 rounded portions and secured to said cross-pieces, and the wagon-body divided longitudinally into two sections, each of said sections being secured to one of said beams, substantially as shown and described. 75

3. In a dumping-wagon, bolsters secured to the wagon-axles, cross-pieces secured to said bolsters having grooves near their ends, a beam secured to the center of said cross-pieces, transverse bars secured to said beam, 80 loops secured to the ends of said bars, beams having rounded portions journaled in said loops and resting in the grooves in said cross-pieces, straps secured to the cross-pieces and passing around said beams, and the wagon- 85 body divided longitudinally into two sections, each of said sections being secured to one of said beams, substantially as shown and described.

4. In a dumping-wagon, bolsters secured to 90 the wagon-axles, cross-pieces secured to said bolsters having grooves near their ends, a beam secured at the center of said cross-pieces, transverse bars secured to said beam, loops secured to the ends of said bars, beams 95 having rounded portions journaled in said

loops and resting in the grooves in said cross-pieces, straps secured to the cross-pieces and passing around said beams, boards secured to each beam forming one-half the floor of the wagon-body and one side thereof, the end boards made in halves and secured to the respective floor and side boards thus forming the body in two independent longitudinal sections, and sockets secured to each side

board to receive a lever to turn the section 10 on the journaled beam, substantially as shown and described.

In testimony whereof I hereto affix my signature in the presence of two witnesses.

ABNER CAREY.

Witnesses:

T. B. FOOTE,
IRA TUTTLE.
